ADJUSTABLE LOUNGE

Arthur J. Geddings, 205 W. Broadway,
Myrtle Beach, S.C. 29577

Filed Feb. 17, 1971, Ser. No. 116,299

Term of patent 14 years

Int. Cl. D6—02

U.S. Cl. D6—37

Fig. 1

Fig. 2

Fig. 3

Fig. 6

FIG. 1 is a perspective illustrating the design of the present invention.

FIG. 2 is a side elevation thereof on a slightly enlarged scale.

FIG. 3 is a bottom plan view.

FIG. 4 is a perspective similar to FIG. 1 and illustrating a portion of the lounge in elevated position.

FIG. 5 is a perspective from one end.

FIG. 6 is an end elevation of the opposite end with the lounge in collapsed position.

The side not illustrated is a mirror image of the side elevation of FIG. 2.

I claim:

The ornamental design for an adjustable lounge, as shown and described.
